(57) **CLAIM**

The ornamental design for a carrier jig, as shown and described.

DESCRIPTION

FIG. 1 is a top perspective view of a carrier jig showing our new design.

FIG. 2 is a front view.

FIG. 3 is a back view.

FIG. 4 is a left side view.

FIG. 5 is a right side view.

FIG. 6 is a top plan view; and,

FIG. 7 is a bottom plan view.

The present design relates to a carrier jig which is fixed inside of an evaporator and heats a carrier. The material of the present design is metal.
